UNITED STATES PATENT OFFICE.

LOUIS ELIE SEIMBILLE, OF PARIS, FRANCE.

ELECTRIC WATER-HEATER.

1,383,034.

Specification of Letters Patent. Patented June 28, 1921.

Application filed September 24, 1918. Serial No. 255,520.

To all whom it may concern:

Be it known that I, LOUIS ELIE SEIMBILLE, abbot, of 42 Rue du Montparnasse, Paris, France, have invented Electric Water-Heaters, of which the following is a full, clear, and exact description.

This invention relates to electric water heaters and has for its chief object to provide a cheap, compact and efficient heater whereby water or any other liquid may be rapidly brought to the desired temperature without undergoing any chemical modification.

A further object is to provide an improved heating element having a very considerable heating surface but a very small volume, and so constructed that although the electric resistance forming part thereof is easily accessible from the outside, said resistance 20 does not come into direct contact with the water.

These and other objects, which will be apparent from the following description, are accomplished by placing in a receptacle of small capacity a flat heating element comprising a thin metal wire strip, preferably bent zigzagwise, and clamped between two thin sheets of mica which are united at their lower and side edges to form a flat watertight pocket of insulating material. The receptacle is provided at the bottom with a water supply pipe and at the top with a discharge pipe which is of greater cross-sectional area than the supply pipe to prevent 30 the water spouting out under high pressure. The insulating pocket in which the resistance wire or strip is arranged is open at the top, but the upper edges of the pocket extend above the level of the discharge pipe 40 so that the water never touches the resistance wire or strip. When desired, two or more mica covered elements may be connected in series or in parallel.

With the arrangement described a considerable heating surface is obtained and nothing but a very thin sheet of insulating material separates the resistance from the water, so that the heat generated in the resistance element is immediately transmitted 50 to the water without any loss. In order to assist in distributing the heat within the water, the insulating pocket containing the resistance element may be clamped between two thin metal plates which are preferably 55 provided with vertical corrugations to permit of the water freely circulating between

the metal plates and the adjacent sheets of mica.

The flow of water through the supply pipe may be controlled by means of a 60 cock or faucet connected with a switch for controlling the supply of current to the resistance. By using a two-pole switch adapted to be closed as soon as the cock is opened the temperature of the water may 65 be varied at will by varying the position of the cock and, consequently, the rate of flow of the water.

This apparatus permits of heating liquids to any desired temperature within a few 70 seconds and is capable of prolonged use without deteriorating.

The apparatus is shown by way of example in the accompanying drawing in which:—

Figure 1 is a perspective view of the apparatus the walls of the receptacle being partly broken away to reveal its contents.

Fig. 2 shows, detached in elevation, the heating element with one sheet of mica and 80 one corrugated metal sheet partly removed.

Figs. 3 and 4 are respectively sections on the lines A—A and B—B of Fig. 2.

As shown in the drawing the apparatus is composed of a receptacle *a* in which the 85 transformation of the current into heat is effected. This receptacle has a capacity strictly sufficient to contain the heating element hereinafter referred to. It is preferably of earthenware, porcelain, steatite or 90 any other material which is not a conductor and is not attacked by boiling water.

The water is fed by the pipe *b* which opens into the lower part of the receptacle *a*, and it runs away through the pipe *c* at the upper 95 part of the receiver. The pipe *c* is of a greater sectional area than that of the pipe *b* for the purpose previously pointed out.

The receptacle *a* contains the heating element which is constituted by a resistance 100 strip *d* clamped between two thin sheets of mica *e*, *e* which in turn are clamped between the corrugated metal sheets *h*, *h*.

The resistance *d* comprises a metal ribbon of any nature obtained for example by rolling out a wire or cutting up a very thin plate. It is tightly packed between two rectangular sheets of mica *e*, *e*, likewise very thin, the lateral edges *f*, *f* and the lower edges *g* of which are soldered or stuck together by any suitable means, for example by the aid of a waterproof mastic, of a

vitrified material, mechanical packing or the like, thus forming an extremely thin pocket which is both insulating and fluid-tight on three of its sides.

5 The sheets h , h , also very thin are made of metal not attacked by water and slightly corrugated or folded in a vertical direction. These metal sheets h , h are for the purpose of distributing the heat more rapidly than 10 the mica which is a bad conductor, while permitting the ascending water to circulate freely and become heated by direct contact with the sheets of mica e , e .

15 The ends i , i of the resistance d are prolonged above the upper open edge of the pocket and end at the terminals j , j connected to the source of the current.

20 The heating element thus constituted is arranged in the receptacle a in such a way that the level of the water never reaches the upper open edge of the pocket and can therefore never come into contact with the resistance d .

25 It must be understood that there may also be arranged in the receptacle a several of these heating elements grouped in parallel or in series according to the nature and the section of the resistance or the power of the apparatus.

30 The supply of the water to the apparatus is regulated by a cock h by the aid of which the temperature of the water may be graduated at pleasure by opening it to a greater or lesser extent.

35 The current is sent into the apparatus by a two-pole switch which is preferably integral with the cock h as in the example shown. To this end, the switch comprises two arms l , l keyed upon an extension of 40 the spindle m of the cock h . As soon as the cock is opened to any extent, the switch arms l , l are engaged between the elastic contact tongues n , n' of the studs o , o and o' , o' which are respectively connected to the 45 source of current and to the terminals j , j to which are connected the ends i , i of the resistance d .

50 In consequence of this arrangement the operator has only to work the cock h to give a passage simultaneously to the water and the current.

55 By opening more or less the cock h the apparatus is supplied with a current which is always constant but with a variable quantity of water, in such a way that it is possible to submit to the action of the current, during a given period of time, a varying quantity of water, which obviously allows of its temperature being graduated according to requirements.

60 It will be understood that the form and the arrangement described and shown of the cock and of the switch are only given by way of example and that any suitable modifications may be made in them, also in all

the other constituent elements of the apparatus.

65 During the operation of the apparatus the small quantity of water admitted into the receptacle a is heated by contact with the heating elements, absorbs all the calories produced and escapes through the pipe c ; it is replaced without interruption by the ascending column of water which constantly goes on cooling the resistance and 70 running away when heated to the desired extent.

75 The apparatus may be electrically insulated from the supply pipe, by a pipe of any insulating material such as ebonite, 80 porcelain, caoutchouc, or the like.

Claims:

1. An apparatus for heating water electrically and almost instantaneously, comprising in combination, a casing of small 85 capacity, an inlet tube near the lower part of said casing, a discharge tube near the upper part of the said casing and having a cross-section greater than that of the water inlet tube, a heating element in the said casing comprising an electric resistance and a thin layer of insulating matter forming an envelop surrounding the said resistance, and metallic sheets engaging the sides of the said envelop and allowing circulation of water 90 in contact therewith.

2. An apparatus for heating water almost instantaneously comprising in combination, a casing of small capacity, an inlet tube for water connected to the lower part of the casing, a discharge tube near the upper part of the said casing and having a cross-section greater than that of the water inlet tube, a heating element in the said casing, comprising a laminated metallic wire or metal ribbon held between two thin plates of mica which form a flat water-tight envelop open at its upper end and extending from a point near the bottom of the casing to a point 100 above the level of the discharge tube, and metallic sheets engaging the sides of the said envelop and having corrugations for the circulation of the water in contact with the envelop.

3. An electric heating apparatus comprising, a casing of small capacity, a water inlet tube connected to the lower part of this casing, a discharge tube near the upper part of the said casing and having a cross-section greater than that of the water inlet tube, a 115 removable heating element placed in the casing and comprising a metallic laminated wire or a metal ribbon folded in zig-zag fashion and held between two thin mica sheets connected at their lower and side 120 edges so as to form a flat water-tight envelop open at the upper end and extending from a point near the bottom of the casing to a point above the level of the discharge tube, and means for distributing heat com- 125 130

prising thin metallic plates with vertical corrugations solidly engaging the envelop while enabling vertical circulation of water in contact with the sides of the said envelope.

The foregoing specification of my "apparatus for the rapid heating of water, more

especially of water not undergoing any chemical modification" signed by me this 24th day of August, 1918.

LOUIS ELIE SEIMBILLE.
